UNITED STATES PATENT OFFICE.

WILLIAM H. ZORN, OF HARRISBURG, NEBRASKA.

END-GATE ROD.

1,247,778.

Specification of Letters Patent. Patented Nov. 27, 1917.

Application filed April 16, 1917. Serial No. 162,387.

To all whom it may concern:

Be it known that I, WILLIAM H. ZORN, a citizen of the United States, residing at Harrisburg, in the county of Banner and State of Nebraska, have invented a new and 5 useful End-Gate Rod, of which the following is a specification.

The invention relates to improvements in end gate rods.

10 The object of the present invention is to improve the construction of end gate rods and to provide a simple, inexpensive and efficient one, designed to dispense with the use of a nut, and adapted to be quickly taken out and replaced and capable of affording a firm and secure connection between the sides of a wagon body.

15 The invention consists in the construction and novel combination and arrangement of parts, hereinafter fully described, illustrated in the accompanying drawings and pointed out in the claims hereto appended.

In the drawings:

20 Figure 1 is a perspective view of a portion of a wagon body provided with an end gate rod constructed in accordance with this invention.

25 Fig. 2 is a rear elevation, partly in section.

30 Like numerals of reference designate corresponding parts in all the figures of the drawings.

1 and 2 designate sections of an end gate rod, and these sections, which are designed 35 to extend across a wagon body, as illustrated in Fig. 1 of the accompanying drawings, have their inner portions overlapped and provided with eyes 3 and 4 bent at right angles and receiving and forming guides 40 for the rods or sections. Each eye extends from the inner end of one rod section and receives the other rod section, and by this construction, the rod sections are adapted to slide longitudinally on each other. The 45 overlapped inner portions of the rod sections receive a coiled spring 5, which is interposed between the eyes 3 and 4, and which is compressed when the end gate rod is in position, as illustrated in Fig. 1 of the accompanying drawings.

50 The outer ends 6 and 7 of the rod sections are provided with slots or openings, adapted to receive keys 8 and 9, of the wagon body, whereby the said rod sections 55 are connected with the sides 10 of the body.

The keys, which are preferably connected with the sides 10 of the body by short chains, are recessed between their ends and when in position, the shoulders formed by the recesses, extend beyond the outer ends of the 60 slots or openings and prevent the pins or keys from becoming accidentally disengaged from the outer ends of the rod sections.

The sides of the wagon body are provided with the usual cleats 11, to form ways 65 for the end gate 12, and the latter is provided at its outer face with vertical cleats or bars 13, having perforations 14, for the reception of the rod sections. The sides of the wagon body are also provided with perforations, and preferably have wear plates 70 15, secured to their outer faces to protect the sides 10.

The rod sections are adapted to slide inward and outward to engage them with and 75 disengage them from the sides of the wagon body, and in applying the end gate rod, the rod section 1 is first moved outward and locked by the pin or key 8. The other 80 rod section is then forced outward against the action of the spring and is locked in a similar manner by the other pin or key 9. The spring is designed to be of sufficient strength to afford a firm connection, and it will maintain the sections securely in 85 engagement with the keys or pins.

In order to enable the spring to be readily compressed to engage the key 9 with the rod section 2, and remove it therefrom, a lever 16 is employed. This lever, which is 90 fulcrumed at its lower end 17, is curved and is slotted to receive the rod section 1, and its upper end extends above the end gate rod and is adapted to be readily grasped by the operator to engage the lever with the 95 eye 4 of the rod 2, to compress the spring sufficiently to free the pin or key 9. After the pin or key 9 is removed, the end gate rod may be moved in the direction of the 100 pin or key 8 to release the latter. Both rod sections may then be pushed inward to the position illustrated in Fig. 2 of the accompanying drawings. The opening 18 of the lever may be formed in any suitable manner, and the lower end 17 is provided with a 105 suitable eye for the reception of the pivot 19.

It will be seen that the end gate rod is exceedingly simple and inexpensive in construction, that it is adapted to be quickly operated to engage it with and disengage it 110

from the sides of a wagon body, and that it forms a firm and secure connection between the said sides. It will also be apparent that it dispenses with a nut and threads and that it does not have to be removed from the end gate.

What I claim is:

1. A device of the class described comprising two rod sections having overlapped slidably connected inner portions, means for detachably connecting the outer ends of the rod sections with the sides of the wagon body, a spring on the overlapped inner ends of the rod sections to move them together, and manually operable means for sliding one rod section and compressing the spring, substantially as described.

2. A device of the class described comprising two rod sections having overlapped inner ends slidably connected together, a spring disposed on the overlapped inner ends of the rod sections and engaging the same, and means for connecting the outer ends of the rod sections with the sides of a wagon body, substantially as described.

3. In a device of the class described, the combination with a wagon body having an end gate, of an end gate rod extending through the sides of the wagon body and composed of two sections having overlapped inner ends and provided at their outer ends with slots or openings, keys removably arranged in the slots or openings of the rod sections, and a coiled spring disposed on the

inner ends of the rod sections and engaging the same, substantially as described.

4. A device of the class described comprising an end gate rod composed of two sections having overlapped slidably connected inner portions, a spring engaging the overlapped inner portions to move the rod sections together, means for connecting the outer portions of the sections with the sides of a wagon body, and a lever arranged to engage one of the sections and adapted to compress the spring, substantially as and for the purpose described.

5. In a device of the class described, the combination with a wagon body having an end gate, of an end gate rod composed of sections having overlapped inner portions, a spring engaging the latter, means for connecting the outer portions of the sections with the sides of the body, and a curved lever fulcrumed at its lower end on the end gate and provided with a longitudinal opening receiving one of the sections, said lever being adapted to engage the inner end of the other section to compress the spring, substantially as described.

In testimony that I claim the foregoing as my own, I have hereto affixed my signature in the presence of two witnesses.

WILLIAM H. ZORN.
